CLOSURE CLEANING APPARATUS

William H. Newey, Hingham, Mass., assignor to
Pneumatic Scale Corporation, Limited, Quincy,
Mass., a corporation of Massachusetts

Application July 19, 1938, Serial No. 219,993

2 Claims. (Cl. 226—88.1)

This invention relates to a closure cleaning apparatus.

One object of the invention is to provide novel and highly efficient apparatus for pneumatically cleaning closures and particularly closures of the type adapted to be applied to containers such as bottles and which finds particular use in removing from new closures the dust and other foreign matter which may have accumulated therein during the manufacture thereof.

A further object of the invention is to provide a novel closure feeding mechanism in which provision is made for pneumatically cleaning the closures prior to the application thereof to a container in a novel, simple and practical manner.

With these objects in view and such others as may hereinafter appear, the invention consists in the apparatus for cleaning closures and particularly bottle caps, in the closure cleaning and feeding mechanism and in the various structures, arrangements and combinations of parts hereinafter described and particularly defined in the claims at the end of this specification.

In the drawing illustrating the preferred embodiment of the invention, Fig. 1 is a plan view of a sufficient portion of a closure applying machine embodying the present invention to enable the same to be understood; Fig. 2 is a longitudinal cross-sectional view of a portion of the closure feeding apparatus shown in Fig. 1; Fig. 3 is a detail view of the cleaning apparatus, and Fig. 4 is an enlarged view in cross-section on the line 4—4 of Fig. 3 illustrating the cleaning nozzle and valve mechanism.

In general, the invention contemplates a novel and practical apparatus for pneumatically cleaning closures such as bottle caps prior to application to a container, and which finds particular use in removing from new bottle caps the small particles of dust and other foreign matter which may have accumulated therein during the process of manufacture or while in process of shipment or in storage. In the improved closure cleaning apparatus provision is made for directing a blast of air into the interior of the closure to the end that the dust may be removed by the air current. In its preferred form the invention is embodied in a machine for applying closures to containers in which provision is made for pneumatically cleaning successive closures as they are being fed to the closure applying mechanism. The cleaning apparatus is preferably operatively connected with the mechanism for feeding the closures to the applying machine to the end that a blast of air is released to clean the interior of a closure each time a closure is withdrawn from the delivery end of the closure feeding mechanism.

Referring now to the drawing, the different features of the invention are illustrated as em-

bodied in a closure applying machine having provision for automatically feeding successive closures to the closure applying mechanism and except as to such details as are hereinafter pointed out, the illustrated closure handling and applying machine may comprise any of the usual forms of such apparatus now upon the market. Reference is made to the United States patent to Arthur Clarence Everett, No. 2,082,048, dated June 1, 1937, for the details of construction and mode of operation of such a prior art closure applying machine.

In the operation of the prior art closure handling and applying machines, as illustrated in the Everett patent above referred to, a bulk supply of the closures is stored in a hopper from which they are individually withdrawn and deposited right side up in a guide chute. As is generally known, such guide chutes are provided with mechanism for releasing one closure at a time, in timed relation to the operation of the closure applying machine and provision is made for transferring each closure from the end of the chute to a position to be received by a revoluble closure applying chuck. Inasmuch as many portions of the closure handling and applying machine of themselves constitute no part of the present invention, it has been deemed sufficient to illustrate only such portions of the machine as will enable the present invention to be understood.

As herein illustrated, the closures 10 are deposited in a guide chute indicated generally at 14. The guide chute is mounted upon a supporting bar 16 one end of which is attached to the frame of the closure feeding hopper, not shown. The lower end of the bar 16 is suspended from an arm 18 secured to the top of a vertical shaft 20 forming part of the closure applying machine. The closures are guided in their movement down the chute 14 between adjustable rails 22, 24. A top rail 38, capable of vertical adjustment, is provided to keep the closures down between the guides.

Provision is made for releasing one closure at a time from the end of the chute 14 in timed relation to the operation of the closure applying machine and as herein shown, the closure releasing mechanism comprises a hooked finger 52 arranged to be raised within the endmost closure of the line to hold the closures back and provision is made for lowering the finger at the proper time in order to release the endmost closure to be transferred to the closure applying mechanism. The finger 52 is adjustably secured to a link 54 which is mounted for movement such that the finger will move with substantially a straight line motion. As herein illustrated, the link 54 is pivotally supported at its ends by arms 56, 58 of bell crank levers 60, 62, the second arms of the bell cranks being connected together by a

link 64. The mechanism is operated through connections from a cam 80 mounted upon a vertical shaft 92 of the closure applying machine and as herein shown, a shaft 65 upon which the bell 5 crank 62 is secured, is provided with a bevel gear 68 which meshes with a bevel gear 70 fast upon a rocker shaft 72 mounted in a bracket 74 attached to the supporting bar 16. A lever 75 also secured to the shaft 72 is connected to a lever 76 by a link 78 and the lever 76 is rocked by the cam 80 cooperating with a roller 82 carried by a lever 84.

In the illustrated embodiment of the invention, the closure applying mechanism is provided with 15 four closure applying heads or chucks so that for each revolution of the continuously revoluble mechanism of the closure applying machine about the vertical shaft 20 it is necessary to provide four closures. As herein shown, the vertical cam 20 shaft 92 upon which the cam 80 is mounted is arranged to be driven from the closure applying machine at a ratio of 2 to 1 through a train of gears 96, 97. The cam 80 being provided with 25 two lobes thus causes four closures to be released at each revolution of the closure applying mechanism.

The mechanism for transferring the closures from the end of the closure feeding chute to the jaws of the closure applying chucks while the 30 latter are revolving and for applying the closures to the containers is fully illustrated and described in the Everett Patent No. 2,082,048, above referred to and is herein indicated generally by transferring arms 100 mounted upon vertical 35 rods 102 carried by a revolvable portion of the closure applying mechanism. The arms 100 are arranged to be rocked outwardly to a position to remove a closure from the end of the chute by a stationary cam 104 with which the rollers 106, 40 carried by the arms 108, cooperate during the revolvable movement of the latter. The low portion 110 of the cam 104 permits the transferring arms 100 to swing inwardly into alignment with the closure applying chucks to permit the latter 45 to receive the closure.

In accordance with the present invention, the apparatus for pneumatically cleaning the closures is herein indicated generally at 120 and is supported in operative relation to the closures 50 10 by a bracket 122 attached to the supporting bar 16. As herein illustrated, the cleaning mechanism comprises an air nozzle 124 supported in a housing 126 and which is in communication with any usual or preferred source of air supply, such as a blower 128 driven by a motor 130. The blower is connected to the air nozzle through a flexible hose 132 and through a hole 134 in the housing 126 leading to the nozzle. Although, in 55 practice, a constant stream of air may be utilized for pneumatically cleaning the interior of the closures as they are advanced past the mechanism 120, it is preferred in the illustrated embodiment of the invention to release a blast of air in timed relation to the movement of the closures 60 through the closure feeding chute. To this end, a rotary valve member 136 having a port 138 is mounted in the housing 126 and provision is made for rocking the rotary valve member so that each time a closure is released from the end of the 65 chute the port 138 will be in alignment with the hole 134 in the housing and so that when the 70

closure releasing mechanism is in its raised position, to hold the closures back, the air supply to the nozzle 124 will be cut off. As herein shown, the valve member 136 is retained in the housing by a cover 140 secured to the housing by screws 5 142 and a rocker shaft 144 formed integrally with the valve member is journaled in the hub 145 of the cover 140. The valve is preferably operated through connections from the closure releasing mechanism and, as herein shown, a lever 148 fast on the end of the rocker shaft 72 is connected by a link 150 to a lever 152 keyed to the valve shaft 144. In operation, when the closure releasing mechanism is operated to release a closure from the end of the chute, the 10 rotary valve is rocked clockwise, as viewed in Fig. 3, to align the port 138 with the hole 134 in the housing and as the closures move forward a blast of air is released through the orifice 154 in the air nozzle. The discharge of air into the 15 interior of the closure causes the foreign particles to be blown downwardly and outwardly and, in practice, any usual or preferred means may be employed for collecting and removing the dust from the area surrounding the cleaning 20 mechanism such as vacuum controlled means, not shown. When the closure releasing mechanism is in its raised position, the valve member is rocked counter-clockwise to remove the port 138 from alignment with the hole 134 in the 25 housing and the air is shut off.

From the description thus far it will be observed that the illustrated cleaning apparatus is adapted to pneumatically clean the closures in a simple, sanitary and efficient manner and finds 30 particular use in connection with a closure applying machine having provision for automatically feeding the closures to the closure applying mechanism.

While the preferred embodiment of the invention 40 has been herein illustrated and described, it will be understood that the invention may be embodied in other forms within the scope of the following claims.

Having thus described the invention, what is 45 claimed is:

1. The combination with closure feeding mechanism comprising a feed chute and mechanism for controlling the delivery of successive closures therefrom, of an air nozzle mounted to direct an air stream into the interior of successive closures passing through said chute, means for supplying air under pressure to said nozzle, an air valve controlling the flow through said nozzle and connections between the air valve and the closure 55 delivering mechanism for opening and closing the valve in timed relation to the movements of said closures.

2. The combination with closure feeding mechanism comprising a feed chute and mechanism 60 for controlling the delivery of successive closures therefrom, of an air nozzle mounted to direct an air stream into the interior of successive closures passing through said chute, means for supplying air under pressure to said nozzle, and means 65 operatively connected with the closure delivery mechanism for controlling the flow of air through said nozzle arranged to release successive blasts of air in timed relation to the movements of said closures.

WILLIAM H. NEWHEY.
